OR D17,389 EX

DESIGN.

—o—
S. M. STEVENS.

BUTTON BADGE.

No. 17,389.

Patented June 14, 1887.

UNITED STATES PATENT OFFICE.

SAMUEL M. STEVENS, OF TERRE HAUTE, INDIANA.

DESIGN FOR A BUTTON-BADGE.

SPECIFICATION forming part of Design No. 17,389, dated June 14, 1867.

Application filed January 31, 1887. Serial No. 226,091. Term of patent 3½ years.

To all whom it may concern:

Be it known that I, SAMUEL M. STEVENS, a citizen of the United States, residing at Terre Haute, in the county of Vigo and State of Indiana, have invented and produced a new and original Design for Button-Badges for the "Order of Brotherhood of Railroad Brakemen;" and I do hereby declare the following to be a full, clear, and exact description of the invention, such as will enable others skilled in the art to which it appertains to make and use the same.

This badge relates to those which are worn like a button—that is, in the button hole usually formed in the lapel of a coat—although, if desired, a pin may be attached thereto and the badge pinned to the coat or vest of the wearer.

The badge consists of a star-like figure having eight points, *a*. Two circular lines, *b* *b'*, are formed on the face of the badge, between which a circular field is left, having thereon a panel for any suitable letters or inscription. On four of the points of the star or the triangular spaces *c*, formed by the circular line *b* and the points of the star, are represented two flags having their standards or staffs crossed, and on the other four crossed links and pins.

In the central field, *d*, appears a bridge or trestle-work supporting the cross ties and rails of a railway-track. The upright supports or trestles for the bridge are made plain or paneled, so that any desired letters or words may be engraved or secured thereon. On the track appears the figure of a man in the act of running and having a lamp in his outstretched hand, from which the rays of light are shown as radiating in all directions.

I claim—

The design for a button-badge herein shown and described, the same consisting of a star having eight points, *a*, the triangular spaces *c*, formed by the same and the circular line *b*, in which are represented crossed flags and links and pins, the circular lines *b* *b'*, the circular spaces formed between the same, the field *d*, having thereon a trestle-work or bridge, the cross-ties and rails, and the figure of a man having a lamp in his outstretched hand.

In testimony whereof I affix my signature in presence of two witnesses.

SAMUEL M. STEVENS.

Witnesses:

C. BRADFORD,

CHARLES L. THURBER.
